[57] **ABSTRACT**

An improved AVC circuit for an alternating voltage amplifier which prevents over-control, and thus temporary blocking of the amplifier circuit, upon the occurrence of a sudden large increase in the amplitude of the input signal to the amplifier. The control voltage generating arrangement of the AVC circuit is constructed so that the time constant of the control voltage is increased proportionately to the increase of the output voltage from the amplifier when ever the output voltage exceeds a predetermined value.

AMPLIFIER WITH IMPROVED AVC CIRCUIT

BACKGROUND OF THE INVENTION

The present invention relates to alternating voltage amplifiers provided with automatic volume control (AVC) circuits. More particularly, this invention relates to an alternating voltage amplifier having an improved automatic volume control circuit whereby temporary blocking of the amplifier due to overcontrol as a result of a sudden increase or jump in the alternating voltage input signal to the amplifier is avoided.

In alternating voltage amplifiers with automatic volume or gain control (AVC) it often occurs that due to a sudden jump or increase in the amplitude of the alternating voltage input signal to the amplifier, the amplifier is temporarily completely blocked, i.e., no output signal can be provided. This may occur, for example, when recording audio signals and particularly voice signals with tape recorders which are provided with an automatic gain control to prevent overloading of the tape.

The cause for the temporary blockage of the amplifier is that the member of the amplifier which is controlled by the AVC voltage (i.e., the controlled amplifier stage) has a time constant t_1 , due to its capacitances and resistances, which is not negligibly small when compared with the time constant t_2 of the control voltage generator in the AVC circuit, so that the controlled member or stage of the amplifier can not follow the above-mentioned jump or increase in the input signal fast enough. This inability of the controlled member or stage of the amplifier to respond quickly enough results in blocking of the amplifier in the following manner:

With a sudden jump in the alternating input voltage signal the amplifier furnishes a correspondingly high alternating output voltage signal, which output signal is fed to the control voltage generator of the AVC circuit which provides an AVC control voltage proportional to the amplifier output signal, and with a time constant t_2 , which is applied to the controlled member of the amplifier. Because of its time constant t_1 , the amplifier causes the amplitude of the alternating output voltage signal to follow the control voltage only after a delay, so that a control voltage is produced which is higher than that required to compensate for the instantaneous alternating input voltage signal. Due to the large amplitude of the control voltage, the amplification of the amplifier is correspondingly reduced so that the amplifier may become blocked. This blocking of the amplifier remains until the control voltage has returned to its nominal value. The time required for this process is determined by the discharge time constant of the capacitor in the AVC circuit which provides the control voltage.

SUMMARY OF THE INVENTION

It is therefore the object of the present invention to provide an improved AVC circuit which prevents the occurrence of above-mentioned blocking of the amplifier upon sudden jumps in the alternating input voltage signal to the amplifier without noticeably increasing the control time of the amplifier.

The above object is accomplished according to the present invention in that the control voltage generator utilized in the AVC circuit has a time constant which automatically increases with increasing alternating

5 input voltage to such an extent that, independent of the value of the alternating input voltage, no over-control takes place and the above-mentioned blocking of the amplifier is thus avoided. In this way the generation of the control voltage information is slowed down until the AVC control circuit has been stabilized.

10 With the optimum solution of this problem the time constant t_2 of the control voltage generator must automatically increase starting from a predetermined alternating amplifier output voltage in proportion with this alternating output voltage.

15 The required automatic increase in the time constant of the control voltage generator is accomplished most easily according to the invention by limiting the charging current for the capacitor furnishing the control information. In order to achieve this result according to a preferred embodiment of the invention, the control voltage generator of the AVC circuit comprises a transistor connected as a collector detector circuit with the above-mentioned charging capacitor connected in series with its emitter current path and an ohmic resistor connected in its collector current path to limit the charging current to the capacitor.

25 BRIEF DESCRIPTION OF THE DRAWINGS

FIG. 1 is a block diagram illustrating a conventional amplifier with an AVC circuit.

30 FIG. 2 is a schematic diagram of a control voltage generator for the AVC circuit according to the preferred embodiment of the invention.

DESCRIPTION OF THE PREFERRED EMBODIMENTS

Referring now to FIG. 1, there is shown an amplifier V with settable member or controllable stage S whose time constant t_1 is formed by internal RC elements and/or by the coupling capacitor C_1 and resistor R_1 for the supply of the AVC control voltage. The amplification of the amplifier is a function of the control voltage V_R which is derived in the control voltage generator R having a time constant t_2 from the alternating output voltage E_o of the amplifier. This alternating output voltage signal E_o is fed to the input of the AVC control voltage generator R via a capacitor C_2 . The slope of the control curve, i.e., the ratio of the amplification difference ΔV (with $V = E_o / E_i$) to the control voltage difference ΔV_R is selected to be high enough that only a slight change in the control voltage is required to accomplish the desired control function in the amplifier.

55 The known amplifiers of this construction with automatic volume control operate faultlessly only when the time constant t_1 of the amplifier is substantially less than the time constant t_2 of the AVC control voltage generating circuit R and thus may be considered negligible. With this relationship, a sudden increase of the input voltage E_i to twice its value will be compensated in a time period T which depends only on the time constant t_2 of the control voltage generator. A sudden jump increase in the input voltage E_i to 100 times its value, however, is compensated in approximately one one-hundredth T since the voltage offered to the control voltage generator R is also increased 100 times, but the control voltage V_R required to change the amplification of the amplifier requires only a very slight adjustment with the large slope of the control curve.

Let it now be assumed that the setting member or controlled stage S has a time constant t_1 which is not negligibly small when compared with the time constant t_2 . The time constant t_2 of the control voltage generator is assumed to be so selected that with low input voltages E_i an increase of E_i to twice its value is compensated in the above-mentioned time T under consideration of the time constant t_1 of the setting member S. Contrary to the conventionally known systems however, according to the present invention an increase in the input voltage E_i and thus momentarily also in the output voltage E_o of the amplifier (assuming linear amplification) to 100 times its value, also increases the time constant t_2 by 100 times so that the control of the sudden change in the input voltage E_i again occurs in the time period T (not as previously in one one-hundredth T). Blocking of the amplifier is thus avoided since the effective time constant t_2 of the control voltage generator R is now substantially larger than the time constant t_1 of the setting member or controllable stage S.

Experiments in practice with an automatically controlled amplifier having a time constant for the controlled stage S of $t_1 = 20$ ms and a control voltage generator R according to the present invention having a time constant $t_2 = 100$ ms for low input voltages E_i produced, a stabilization in approximately 150 ms when E_i suddenly increased by a factor of 2; a stabilization in approximately 140 ms when E_i suddenly increased by a factor of 10 and a stabilization in approximately 120 ms when E_i suddenly increased by a factor 100, all without the amplifier being blocked.

FIG. 2 shows an example for the circuitry for a control voltage generator R according to the present invention which differs by the provision of resistor R_2 in collector current path of the transistor 7 from the conventional design of a collector detector circuit.

With this circuit, the alternating voltage E_o is fed to the base of the transistor T via a capacitor C_2 and a resistor R_3 connected in series. During the positive half-cycle of signal E_o the charging current I_L flows from the source of operating voltage V_B via the collector-emitter circuit path of transistor T into the charging capacitor C_3 connected to the emitter of the transistor T and there generates the control voltage V_R . For the sake of completeness the discharge resistor R_4 for capacitor C_3 is also shown. This resistor R_4 is generally of such a size that it need not be considered in determining the charging time constant of the capacitor C_3 . In the conventional design of a collector detector, (i.e., R_2 is short-circuited) the maximum charge current I_L is

$$I_L \text{ max} = \frac{1}{2} \cdot E_o / R_3 \cdot B, \quad (1)$$

where B is the current amplification factor of the transistor T in common-emitter connection and the factor one-half considers that a charging current flows only during the positive half-cycle of E_o . The charging time constant t_L of the conventional circuit is

$$t_L = (E_o / I_L \text{ max}) \cdot C_3 = (2/B) \cdot R_3 C_3 \quad (2)$$

According to the present invention, the dependence of the charging time constant t_L on the amplitude of the alternating voltage E_o is achieved by connecting an ohmic resistor R_2 between the collector of the transistor T and the battery voltage source V_B . The

charging current I_L is thus limited to

$$I_L' \cong \frac{1}{2} \cdot (V_B / R_2) \quad (3)$$

and this results in the charging time constant

$$t_L' = (E_o / (I_L') \cdot C_3 \cong 2 \cdot (E_o / V_B) \cdot R_2 C_3. \quad (4)$$

As can be seen from Equations 1 and 3, the charging time constant t_L of the control voltage generator R is

$$t_2 = t_L$$

as long as the alternating voltage amplitude of the amplifier output signal is

$$E_o \leq V_B \cdot (R_3 / (B \cdot R_2)) \quad (5)$$

If the amplitude exceeds this value, then according to the invention

$$t_2 = t_L' \cong 2 \cdot (E_o / V_B) \cdot R_2 C_3 \quad (6)$$

and is thus proportional to the increased amplitude of the alternating voltage E_o .

In Equation 6 the components may have, for example, the following values:

$$\begin{aligned} C_2 &= 1 \mu\text{F} \\ C_3 &= 250 \mu\text{F} \\ R_2 &= 15 \text{ KOhm} \\ R_4 &= 2 \text{ KOhm} \\ V_B &= +12 \text{ V} \end{aligned}$$

It will be understood that the above description of the present invention is susceptible to various modifications, changes and adaptations, and the same are intended to be comprehended within the meaning and range of equivalents of the appended claims.

I claim:

1. In an amplifier for alternating voltages which amplifier is provided with an automatic volume control (AVC) circuit responsive to the output signal thereof, and wherein the time constant of the stage or stages of the amplifier which is controlled by the AVC voltage is sufficiently large relative to the normal time constant of the AVC circuit so that temporary blocking of the amplifier would normally occur upon the occurrence of a sudden large increase in the amplifier input voltage, the improvement wherein said AVC circuit comprises: a collector-detector circuit including a transistor which is arranged only in the AVC-voltage signal path but not in the forward signal transmission path of said amplifier, said transistor having its base connected to the output of said amplifier and its emitter-collector circuit connected across a source of operating d.c. potential; a charging capacitor connected in the emitter circuit path of said transistor for furnishing the AVC circuit control voltage; and means for limiting the charging current to said capacitor comprising an ohmic resistor connected in the collector circuit path of said transistor, whereby the time constant of said AVC circuit is increased proportionally to the increase in the output voltage signal of said amplifier above a predetermined value so that with increasing input voltage to said amplifier the time constant of the AVC circuit increases to such an extent that, independent of the alternating input signal to said amplifier, overcontrol of said amplifier, and thus blocking of said amplifier, is avoided.
2. The amplifier defined in claim 1 wherein said base of said transistor is connected to the output of said amplifier via an RC series circuit.
